UNITED STATES PATENT OFFICE.

JOHN BENNER, OF PHILADELPHIA, PA., ASSIGNOR TO AMERICAN STOVE
AND HOLLOW-WARE COMPANY, OF SAME PLACE.

DESIGN FOR STOVE.

Specification forming part of Design No. 7,515, dated June 30, 1874; application filed June 10, 1874.
[Term of Patent 7 years.]

To all whom it may concern:

Be it known that I, JOHN BENNER, of the city of Philadelphia, in the county of Philadelphia and State of Pennsylvania, have invented a Design for Stove Castings, (cook-stove,) of which the following is a specification:

The accompanying photographic illustration, to which reference is made, shows the nature of my invention or design.

The main surface of the body of the stove is plain and smooth, while all the joints and angles are made with a finish of moldings of varied sizes, as shown; also, the bodies of the

several doors have edge moldings, and bulged centers with carved figures in the central part of each door, as shown. *a b c d*, the outline of the feet, with ornamental carving *e*, is also clearly shown in the illustration.

What I claim as my invention is—

The ornamental design for a stove, obtained by the combination of the outlines, moldings, and carved figures, as shown.

JOHN BENNER.
